UNITED STATES PATENT OFFICE.

WILLIAM H. CLAYTON AND CHARLES A. LORING, OF ATLANTA, GEORGIA.

SEWING-MACHINE MOTOR.

SPECIFICATION forming part of Letters Patent No. 402,805, dated May 7, 1889.

Application filed June 20, 1888. Serial No. 277,616. (No model.)

To all whom it may concern:

Be it known that we, WILLIAM H. CLAYTON and CHARLES A. LORING, citizens of the United States, residing at Atlanta, in the 5 county of Fulton and State of Georgia, have invented certain new and useful Improvements in Sewing-Machine Motors; and we do declare the following to be a full, clear, and exact description of the invention, such as 10 will enable others skilled in the art to which it appertains to make and use the same.

This invention has relation to motors for sewing-machines and the like, and is designed as an improvement upon the devices shown 15 and described in the Letters Patent granted W. H. Clayton, June 7, 1887, No. 364,216.

The invention will be fully understood from the following description, when taken in connection with the annexed drawings, in which—

20 Figure 1 is a side elevation of the motor constructed according to our improvements, with the drum-gear partly in section to show the spring therein, and the swivel of the brake-rod also in section. Fig. 2 is a plan view of 25 the same, the belt connections being omitted.

Referring by letter to the said drawings, A indicates the main frame, which is suitably formed to support the shafts of the various gears of the operating mechanism, and is provided with feet, as *a*, whereby it may be secured 30 to a suitable base in a convenient position to be connected with a sewing-machine.

Secured to one side of the main frame are 35 two brackets, *b*, which have eyes to form bearings for a crank-shaft, *C*, journaled therein. This crank-shaft, which has its crank *D* at one end, is provided with a vertically-fixed bevel-gear, *E*, which meshes with a vertically-fixed bevel-gear, *F*, secured on one end of the 40 shaft *G*, passing through the drum-gear. The horizontal shaft *G* is suitably journaled in the main frame, and carries loosely thereon a drum-gear, *H*, which revolves around said shaft, the periphery of said drum-gear being 45 provided with teeth for the purpose which will be presently described, and this horizontal shaft *G* is furthermore provided with a vertically-fixed ratchet-wheel, *I*, which is designed to be engaged and prevented from 50 backward movement by a pivoted pawl, *J*, as shown.

K indicates a flat spring, which has one end secured to the shaft *G* and its opposite end secured to the drum-gear, as shown at *d*. It will thus be seen that when motion has been 55 imparted to the main operating-shaft *G*, through the medium of the crank-shaft and bevel-gearing, the spring will be wound upon the said shaft *G*, and prevented from unwinding by the pawl-and-ratchet brake or friction 60 device previously described.

L indicates a horizontal shaft, which is provided with two vertically-fixed gears of different diameters, the smaller one of which meshes with the drum-gear and the larger one 65 with a pinion, *M*, which is also secured to a horizontal shaft, *N*, carrying a larger gear or pinion, *P*, and this latter gear meshes with a smaller pinion, *R*, which is fixed to the shaft carrying the drive-pulley *S*. 70

V indicates an endless drive-belt, which connects the pulley *S* with the band-wheel *W* of a sewing-machine or the like which is to receive motion.

In operation, when it is desired to connect 75 the motor with a sewing-machine or other machine having a band-wheel, it is simply necessary to make the belt connection between the band-wheel of the machine to be run and the pulley *S*, after which the pawl *J* is thrown 80 into the teeth of the ratchet *I*, when by turning the crank-handle *D* the spring will be wound upon the main operating-shaft *G*. Now it will be seen that the action of the 85 spring in its tendency to unwind will rotate the drum-gear *H* around shaft *G*, and which, through the medium of the intermediate gear, will rotate the pulley *S* and drive the belt thereon.

Having described the construction and operation of the motor proper, we will now describe our tension and brake device. 90

e indicates a longitudinal rod, which has a bearing near its forward end in an arm or eye, *f*, fixed to the main frame, and is provided with a threaded portion, as shown at *g*, which is designed to engage an internal thread in an arm, *h*, which latter is also secured to the main frame. This longitudinal rod *e* is provided at one end with a friction eye or 95 loop, *i*, which receives the shaft *T*, bearing the pulley *S*, and at its opposite end with a 100

hand-wheel, *k*. This rod *e* is composed of two parts, which are united by a swivel, *Z*, so that while the threaded part may turn in the threaded eye the part having the friction-eye 5 will move back and forth. It will thus be seen that by means of this rod a brake may be effected or the force of the motor and the machine to which it is connected retarded by turning the said rod in one direction, while 10 the full effect of the spring and its co-operating parts may be attained by turning the said rod in the opposite direction, so as to bring the friction-eye out of engagement with the shaft *T*.

15 Having described our invention, what we claim is—

In a sewing-machine motor, substantially as

described, the combination, with the main frame for supporting the driving-gear, having an internally-threaded bearing, of the band-pulley shaft and the brake-rod composed of two parts united by a swivel, one of the said parts being threaded externally to engage threads in the bearing on the main frame and the other part provided with a friction-eye to receive the said band-pulley shaft, substantially as specified. 20
25

In testimony whereof we affix our signatures in presence of two witnesses.

WILLIAM H. CLAYTON.
CHARLES A. LORING.
